UNITED STATES PATENT OFFICE.

SAMUEL NELSON HOUSE, OF ST. LOUIS, MISSOURI.

COLD-TIRE-SHRINKING MACHINE.

No. 805,798.

Specification of Letters Patent.

Patented Nov. 28, 1905.

Application filed June 24, 1905. Serial No. 266,779.

To all whom it may concern:

Be it known that I, SAMUEL NELSON HOUSE, a citizen of the United States, residing in the city of St. Louis, in the State of Missouri, have invented certain new and useful Improvements in Cold-Tire-Shrinking Machines, of which the following is a full, clear, and exact description, reference being had to the accompanying drawings, forming part of this specification.

My invention relates to that class of machines used for shrinking tires upon vehicle-wheels while they are in a cold condition, the present invention being in the nature of an improvement upon the machine for which Letters Patents of the United States No. 690,523, dated January 7, 1902, and No. 791,693, dated June 6, 1905, were issued.

Figure I is a top or plan view of my machine. Fig. II is a view partly in longitudinal vertical section and partly in elevation. Fig. III is a view, partly in plan and partly in horizontal section, of the wheel-receiving end of my machine. Fig. IV is a side elevation of the wheel-receiving end of the machine. Fig. V is a transverse section taken on line V V, Fig. I. Fig. VI is a perspective view of one of the gripping-wedges used in the machine in inverted position.

A designates the foundation upon which my machine is mounted.

B designates the frame of the machine, which consists of side walls 1, a transverse bed member 2, and a transverse shelf 3, all of said parts being made in the form of an integral casting, thereby rendering them of much greater united strength and stability. At the upper side of the bed member 2 are flanges 2', extending longitudinally of the frame and having their inner faces tapered, thereby furnishing a V-shaped recess between the flanges, the width of which increases inwardly from the outer end of the bed member. Upon the upper side of the bed member 2 and within said recess are ribs 2^a, spaced apart from the flanges 2' for the purpose of furnishing grooves 2^b between the flanges and ribs, as seen in Figs. I and V.

4 designates a reciprocating block that rests upon the shelf 3 of the frame B and upon ledges 1^a, projecting from the inner faces of the frame side walls 1. This reciprocating block opposes the bed member 2 and is arranged for movement toward and away from said bed member. At the upper side of the block 4 are inclined side flanges 5, that are

separated to provide a recess of V shape between them, the wider end of which faces the recess in the bed member 2. In the recess in said block are ribs 6, spaced apart from the side flanges 5 to provide for the presence of grooves 7 between the flanges and ribs. The block 4 is normally held spaced apart from the bed member 2 by an expansion-spring 8, the ends of which are seated in lugs 2^c and 4', 65 projecting, respectively, from the bed member and reciprocating block.

10 is a bridge-plate spanning the space between the bed member and reciprocating block, and 11 represents adjustment-plates, 70 these parts being located between the ribs 2^a and 6 of the bed member and reciprocating block and serving as a rest for the wheel-tire which is to be shrunk. The bridge and adjusting plates are located beneath the tire-gripping 75 wedges, which surmount the bed member 2 and reciprocating block 4 and by which the wheel-tire is engaged to be drawn upon in opposite directions upon the reciprocation of the block 4 toward the bed member. My 80 present invention relates in part to an improvement in these gripping-wedges, as will hereinafter appear.

12 designates a power-lever through the medium of which the reciprocating block 4 is forced toward the bed member 2. This power-lever is provided at its forward end with a head 13, which is journaled in the frame of the machine by means of trunnions 14, cast integral therewith and seated in the frame side 90 walls 1. By casting the trunnions integral with the head of the lever I provide journals of much greater strength for the power-lever, which must withstand great strain in the actuation of the reciprocating block when the 95 tire is being shrunk. To permit of the head of the power-lever, with the trunnions cast integral therewith, being introduced into the solid frame of the machine, I make one of the trunnion-openings in the frame side walls of considerably greater diameter than the diameter of the trunnion that is to fit therein. Provision is thereby made for the ready introduction of the trunnions into their openings, the trunnion last introduced being that 105 which rests in the opening of the largest dimension. The larger trunnion-receiving opening is closed after the trunnions have been seated in the frame by a bearing-block 15, that is shaped to fit the portion of the opening unoccupied by the trunnion therein. The power-lever 12 is actuated by a lever 16, that 110

is geared thereto in the manner described in Letters Patent No. 791,693, hereinbefore mentioned.

- 17 designates a wear-plate (see Figs. II and 5 III) that is placed against the rear end of the reciprocating block 4 and interposed between said block and the nose of the head of the power-lever 12. This wear-plate, which is loosely seated between said members, receives 10 the direct bearing of the nose of the power-lever in order that said lever may operate thereagainst instead of against the reciprocating block. In such position the wear-plate serves to relieve the reciprocating block of 15 wear by the power-lever. The wear-plate being independent of the reciprocating block and detachably fitted thereto may be replaced by a fresh and like plate when it becomes worn and unfit for further service.
- 20 18 designates take-up strips (see Figs. III and IV) which are interposed between the reciprocating block and wear-plate 11, these strips being designed to be introduced into the position stated by passing them through 25 openings in the side walls of the machine-frame after the power-lever has been actuated to force the reciprocating block forwardly in the tire-shrinking action and previous to the next operation of the lever to 30 force the reciprocating block farther forward in continuing the shrinking action. These take-up strips being located between the reciprocating block and the wear-plate 17 are entirely relieved of wear due to the use of 35 said wear-plate in the position stated.
- 19 designates the tire-gripping wedges hereinbefore alluded to, which are seated in the bed member 2 and the reciprocating block 4. These gripping-wedges are in the main of similar form to those shown and described in my 40 patents hereinbefore mentioned, each wedge being provided with a serrated tire-engaging edge 20. It has been found by long-continued practical use of my machine that these 45 wedges as shown and described in the previous patents become rounded at the lower edges of their outer sides, which contact with the members by which the wedges are supported, and that as a result of their becoming 50 so rounded the wedges rock in their seats

when outward pressure is exerted thereagainst in pulling the tire to shrink it. This has resulted in the gripping-wedges kicking out of the bed member and reciprocating block, an action that it is obviously desirable to 55 overcome. For the purpose of overcoming this action I provide each gripping-wedge with a rib 21, located at its bottom and adjacent to its outer side. (See Figs. V and VI.) These ribs extend below the main lower faces 60 of the gripping-wedges and operate in the grooves 2^b and 7 in the bed member and reciprocating block, respectively, while the main portions of the wedges ride upon the ribs 2^a and 6 adjacent to said grooves. The ribs of 65 the wedges being thus located beneath the lines of force against the wedges, all possibility of the wedges kicking from their seats is removed.

I claim as my invention—

1. In a tire-shrinking machine, the combination of a frame having a bed member, a reciprocating block opposing said bed member, a reciprocating-block-actuating power-lever provided with trunnions integral therewith fitting in openings in the sides of said frame, one of which is of greater dimensions than the dimension of the trunnion it receives, and a bearing-block removably seated in the larger of said openings, substantially 80 as set forth.

2. A gripping-wedge for tire-shrinking machines provided with a rib located at its lower side, substantially as and for the purpose set forth.

3. In a tire-shrinking machine, the combination of a frame having a bed member provided with ribs and grooves, a reciprocating block opposing the said bed member and provided with ribs and grooves, gripping-wedges 90 resting upon said bed member and reciprocating-block ribs; said gripping-wedges being provided at their lower sides with ribs arranged to operate in the grooves of said bed member and reciprocating block, substantially as set forth.

SAMUEL NELSON HOUSE.

In presence of—

NELLIE V. ALEXANDER,
BLANCHE HOGAN.
